UNITED STATES PATENT OFFICE.

ISABELLA ALLEN, OF KANSAS CITY, MISSOURI.

MAIL-TYING DEVICE.

982,111.

Specification of Letters Patent. Patented Jan. 17, 1911.

Application filed October 28, 1909. Serial No. 525,007.

To all whom it may concern:

Be it known that I, ISABELLA ALLEN, a citizen of the United States, residing at Kansas City, in the county of Jackson and State of Missouri, have invented certain new and useful Improvements in Mail-Tying Devices, of which the following is a specification.

My invention relates to mail-tying devices, and my object is to provide a simple, inexpensive and durable device of this character, whereby letters and other mail-matter can be quickly and reliably tied into packages for transmission through the mail.

In order that the invention may be readily understood, reference will now be made to the accompanying drawing, in which:

Figure 1 shows a perspective view of the device. Fig. 2 is a vertical central section of the same on line II—II of Fig. 1. Fig. 3 is a front elevation of the device attached to a package of mail-matter.

In constructing the device, I prefer to strike the same from one piece of sheet-steel, so that it may be produced by dies and thus avoid the cost which would result from making the device by hand.

The device consists preferably of a round body portion 1, having longitudinal arms 2 and 3 and a pair of transverse arms 4 radiating therefrom. Arms 2, 3, and 4 are provided with hooks 5, 6, and 7, respectively, struck therefrom, hook 6 being considerably longer than its companions to render it more resilient than the same. Arm 2 is further provided with a hook 2^a, for a purpose which will hereinafter appear.

8 designates a latch pivotally secured to the body portion by a pin 9, and provided at its free end with a rib 10 adapted to depress the free end of hook 6 and engage a V-shaped notch 11 in the upper end thereof.

12 designates a cable which may consist either of cord or flexible wire, attached to

the outer terminal of arm 3, and adapted to be wrapped around packages of mail-matter, as shown in Fig. 3. Cable 12 is provided at its free end with a ring 12^a adapted to engage hook 2^a.

13 designates an opening in body portion 1 to lighten the same and whereby the device may be hung upon a nail or hook when not in use.

In tying up a package of letters or other mail-matter, the device is placed against one side thereof and the cable is wound about the package, and the hooks 5 and 7 which reliably hold it in position. The free end of the cable is then drawn tightly between arm 3 and hook 6, which latter is pressed inwardly against the cable to firmly bind the same between said hook and the arm 3. Latch 8 is then swung around over the hook to hold the same firmly in engagement with the cable, the hook being held in position by rib 10 engaging the V-shaped notch 11 of the upper end of arm 6. The remainder of the cable, if any, is then wound around the package and secured by engaging hook 2^a with the ring 12^a on the end of said cable.

Having thus described my invention, what I claim is:

A device of the character described, consisting of a body portion, arms projecting therefrom, resilient hooks struck from said arms, a cable attached to one of the arms and adapted to engage one of said hooks, and a latch pivotally secured to the body portion and adapted to engage and depress the free end of one of the hooks, to clamp the cable between said hook and its respective arm.

In testimony whereof I affix my signature, in the presence of two witnesses.

ISABELLA ALLEN.
